UNITED STATES PATENT OFFICE

1,922,325

MANUFACTURE OF PAPER

Harold Robert Rafton, Andover, Mass., assignor
to Raffold Process Corporation, a Corporation
of Massachusetts

No Drawing. Application December 11, 1930
Serial No. 501,674

42 Claims. (Cl. 92—40)

This invention relates to the manufacture of sized paper filled with alkaline filler.

The principal object of the invention is to produce sized paper filled with alkaline filler in which 5 the sizing is applied to the paper web.

A further object is to produce sized paper filled with alkaline filler in which rosin size is employed as the sizing agent.

Other objects and advantages of my invention 10 will become apparent during the course of the following description.

It is well known that the ordinary paper making procedure of sizing paper with rosin size and alum in the beater will not size paper filled with 15 alkaline filler.

In my copending application Serial No. 304,168, filed September 5, 1928, now Patent No. 1,803,643, granted May 5, 1931, I disclose a method of employing rosin size to size paper filled with alkaline filler, in which method the fibrous suspension containing rosin size which has been precipitated with alum in the beater is treated with a sizing restoring agent just before the formation 25 of the paper web. In my copending application Serial No. 304,172, filed September 5, 1928, now Patent 1,803,647, granted May 5, 1931, I disclose a method of employing rosin size to size 30 paper filled with alkaline filler, in which method the fibrous suspension is treated with a size precipitant just before the formation of the paper web.

These procedures, as is shown in the above 35 applications, entail the addition of a restoring agent or precipitant under conditions favoring the minimizing of the time and/or intimacy of contact of the constituents of the mix, and thereby avoid the deterioration ordinarily taking place when a rosin size precipitate comes in contact with alkaline filler.

40 I have also found that alkaline filler will not substantially deteriorate or destroy precipitated rosin size if the sizing be applied to the web containing alkaline filler instead of to the dilute suspension which is fed to the web-forming device, and it is this invention which forms the subject matter of the present application.

45 In the practice of my invention a fibrous mix (i. e. a paper making mix) in which alkaline filler is present is fed to the web-forming device of a paper machine, a web is formed, and to this web size and size precipitant is applied. The web is dried and the dried web is finished in any customary manner. The point of application, the method of application, the concentration and 50 amounts of size and size precipitant to be applied,

and other necessary or optional details of my process are fully set forth immediately below.

The size and size precipitant may be applied at any convenient point of the paper machine, either where the web is still in wet condition, e. g. 60 preferably just after the press rolls, or at a point where the water has been substantially removed from the web, e. g. preferably just after the driers, or they may optionally be applied to the paper web subsequent to the paper machine as a separate process.

The size and size precipitant may be applied as indicated to the wet or the dry web but in case of application to the dry web, of course, provision must be made for subsequent removal of the 70 water present in the size and size precipitating solutions, e. g. by passage of the web over driers or by festooning in a hot atmosphere. In any case, after the application of the size and size precipitant the web is subjected to sufficient heat 75 to dry it and it is then finished as desired. Of course if the size and size precipitant are applied to the web on the paper machine while it is still wet, the regular machine driers will ordinarily provide suitable drying means.

80 The size and size precipitant may be applied to the web by any of the various known methods for applying liquids to a paper web such as passing the web through successive troughs or vats containing preferably first the sizing solution and 85 then the size precipitating solution, or by brushes for example rotary brushes, or by contact rolls, or by supply boxes on the press rolls, or by spraying or the like. The method of application employed in any given instance is that which is best 90 adapted for use at the particular point at which the sizing is to be applied and should be chosen with regard to the particular conditions to be met in any given case, all of which will be apparent to one skilled in the art. For example, I have 95 found application by a roll or sprays very convenient methods, especially at a point subsequent to the first press roll.

99 The concentration of the solutions will depend to a certain extent upon the method of employing them and the point of application. For application by rolls the solutions may be more concentrated, for example 5 per cent. or more, but for immersion or for spraying it is more suitable to have them relatively dilute, conveniently approximately 2 to 3 per cent. concentration. The amounts of the two solutions used, while varying as will be apparent with the grade of paper, its fibrous constituents, the percentage of filler, and the like, may however, in general, be stated to be 105 110

approximately the same as the amounts of size and size precipitant used for the same grade of paper and the same percentage of filler, when sizing clay filled paper in the beater. In general 5 the amount of size used may vary from somewhat under one per cent. up to several per cent. or more, calculated as weight of size on the weight of paper. The precipitant may vary from an amount approximately equal to the size up to 10 150 per cent. or more of the size used. I do not however limit myself to the concentrations and percentages mentioned in this paragraph, as they may be widely varied according to circumstances as indicated above and still produce satisfactory results.

As the size and precipitant are preferably applied continuously to the web, suitable means for supplying them to the applying device, e. g. pumps, should be employed, and the amounts applied should preferably vary regularly with the paper machine speed, and be adjustable to the various grades and weights of paper run.

As will be apparent this method of sizing may be combined with other methods for sizing papers 25 filled with alkaline filler, for example those disclosed in my above mentioned two copending applications. At any rate if the machine broke from my process be reintroduced into the fibrous mix from which the paper is made, e. g. in the beater, the addition of a restoring agent or size precipitant, particularly an acidic material such as alum, just prior to web formation is desirable to control the foam resulting from the deterioration or destruction of the sizing in the broke by 30 the alkaline filler.

I have found that it is possible to precipitate the sizing, particularly in the presence of a colloid, and apply the precipitated sizing to the web instead of actually precipitating the sizing in the 35 web, but such procedure seems to take more sizing in certain instances. It is also possible to apply the size and/or size precipitant to the web as it is in the process of formation on the web forming device, preferably after the fibres have 40 been substantially positioned. But whereas I consider such methods to fall within the scope of my invention I do not, however, consider them preferable procedures when my invention is employed on Fourdrinier machines, owing to the fact that 45 the addition of size and size precipitant or precipitated sizing at such point has a tendency to interfere with the proper sheet formation.

I have found at times that it is desirable to 50 apply the size and/or size precipitant to both sides of the web instead of only to one side. I have found that in certain cases this assists in uniformly distributing the sizing throughout the sheet, particularly where the solutions are applied by means of rolls.

60 I may apply either the size or the alum solution to the web first, but I prefer to apply the size first.

In certain cases, particularly where the presence of foam is not a serious detriment, the size 65 may be introduced into the mix prior to the web-forming device, in which case only the size precipitant need be applied at the web. Likewise the procedure may be reversed, applying the precipitant to the mix just prior to the web-forming 70 device and size to the web, but this latter procedure in general requires more precipitant. However, in either of these cases the precipitation actually takes place in the web.

The size I prefer to use is rosin size and my 75 preferred precipitant is alum. Instead of rosin

size I may use any other sizing agent, preferably one precipitable by a size precipitant, as such precipitated sizes, if employed in the usual manner in the beater, are deteriorated if not completely destroyed by alkaline filler in a similar manner to precipitated rosin sizing. Instead of alum as a size precipitant I may use with a measure of success other acidic material such as sulphuric acid, or other metallic salts such as zinc sulphate or sodium bisulphate, or other compounds of aluminum such as aluminum chloride or the like, but I prefer alum.

Where I use the term "solution" in respect to size, I mean to include not only those cases in which the size may be present as a true solution, but also those cases where it may be present in whole or in part as a suspension and/or emulsion.

Where I use the term "rosin size" herein I mean size made by any process from any natural or synthetic resin acid or acids, regardless of the exact composition of the product or the varying composition which different samples may possess.

By the term "alkaline filler" I mean substantially water insoluble filler which when agitated in contact with freshly boiled distilled water, say 100 for an hour, will impart a pH value to such water greater than 7.0, that is, which will be on the alkaline side of the neutral point. Among fillers in this group may be mentioned calcium carbonate, of which lime mud from the causticizing process 105 is one form; calcium carbonate magnesium basic carbonate employed in the paper disclosed in my United States Patent No. 1,595,416, issued August 10, 1926; calcium carbonate magnesium hydroxide disclosed by my United States Patent No. 110 1,415,391, issued May 9, 1922; and other substantially water insoluble normal or basic carbonates of alkaline earth metals, (which expression is herein intended to include magnesium), or compounds, double salts, or other physically associated mixtures of these with one or more other acid soluble materials of a substantially water insoluble nature. By the term "alkaline filler" I also intend to include fibrous material and/or other material such as paper coating constituents 115 or the like containing one or more compounds of the character referred to, such as "old papers" or similar papers, "broke", or the like.

Where in the claims I use the word "web", I means to include not only the already formed 125 web, after it has left the web-forming device, but also the forming web as it exists at any point on the web-forming device.

When I use the word "paper" herein, I use it 130 in the broad sense to include products of manufacture of all types and of all weights and thicknesses, which contain as an essential constituent a considerable amount of prepared fibre and which are capable of being produced on a Fourdrinier, cylinder, or other forming, felting, 135 shaping or molding machine.

While I have described in detail the preferred embodiment of my invention, it is to be understood that the details of procedure, the proportions of ingredients, and the arrangement of steps 140 may be widely varied without departing from the spirit of my invention or the scope of the subjoined claims.

I claim:

1. The method of manufacturing sized paper 145 filled with alkaline filler comprising the inclusion in a fibrous web containing alkaline filler of substantially water-insoluble precipitated sizing material, said inclusion taking place subsequent to the point of delivery to a web-forming device 150

- of the fibrous mix from which said web is formed, and the subsequent drying of said web.
2. The method of manufacturing sized paper filled with alkaline filler comprising effecting the precipitation of size in a fibrous web containing alkaline filler to form substantially water-insoluble sizing, and subsequently drying said web.
3. The method of manufacturing sized paper filled with alkaline filler comprising treating a fibrous web containing alkaline filler with size and size precipitant to form substantially water-insoluble sizing, and subsequently drying said treated web.
4. The method of manufacturing sized paper filled with alkaline filler comprising treating a fibrous web containing alkaline filler with rosin size and size precipitant, and subsequently drying said treated web.
5. The method of manufacturing sized paper filled with alkaline filler comprising treating a fibrous web containing alkaline filler with rosin size and acidic material, and subsequently drying said treated web.
6. The method of manufacturing sized paper filled with alkaline filler comprising treating a fibrous web containing alkaline filler with rosin size and metallic salt, and subsequently drying said treated web.
7. The method of manufacturing sized paper filled with alkaline filler comprising treating a fibrous web containing alkaline filler with rosin size and alum, and subsequently drying said treated web.
8. The method of manufacturing sized paper filled with alkaline filler comprising treating a wet fibrous web containing alkaline filler with size and size precipitant to form substantially water-insoluble sizing, and subsequently drying said treated web.
9. The method of manufacturing sized paper filled with alkaline filler comprising treating a wet fibrous web containing alkaline filler with rosin size and size precipitant, and subsequently drying said treated web.
10. The method of manufacturing sized paper filled with alkaline filler comprising treating a wet fibrous web containing alkaline filler with rosin size and acidic material, and subsequently drying said treated web.
11. The method of manufacturing sized paper filled with alkaline filler comprising treating a wet fibrous web containing alkaline filler with rosin size and alum, and subsequently drying said treated web.
12. The cyclic procedure in a method for manufacturing sized paper filled with alkaline filler comprising the inclusion in a fibrous web containing alkaline filler of precipitated sizing material, said inclusion taking place subsequent to the point of delivery to a web-forming device of the fibrous mix from which said web is formed, the returning of broke from the paper making operation to the fibrous mix prior to web formation, and the addition of a size precipitant to the mix just prior to web formation.
13. The cyclic procedure in a method for manufacturing sized paper filled with alkaline filler comprising the inclusion in a fibrous web containing alkaline filler of precipitated sizing material, said inclusion taking place subsequent to the point of delivery to a web-forming device of the fibrous mix from which said web is formed, the returning of broke from the paper making operation to the beater, and the addition of a size precipitant to the paper making mix just prior to web formation.
14. The cyclic procedure in a method for manufacturing sized paper filled with alkaline filler comprising the inclusion in a fibrous web containing alkaline filler of precipitated sizing material, said inclusion taking place subsequent to the point of delivery to a web-forming device of the fibrous mix from which said web is formed, the returning of broke from the paper making operation to the beater, and the addition of acidic material to the paper making mix just prior to web formation.
15. The cyclic procedure in a method for manufacturing sized paper filled with alkaline filler comprising the inclusion in a fibrous web containing alkaline filler of precipitated sizing material, said inclusion taking place subsequent to the point of delivery to a web-forming device of the fibrous mix from which said web is formed, the returning of broke from the paper making operation to the beater, and the addition of alum to the paper making mix just prior to web formation.
16. The cyclic procedure in a method for manufacturing sized paper filled with alkaline filler comprising treating a fibrous web containing alkaline filler with size and size precipitant, returning broke from the paper making operation to the fibrous mix prior to web formation, and adding a size precipitant to the mix just prior to web formation.
17. The cyclic procedure in a method for manufacturing sized paper filled with alkaline filler comprising treating a fibrous web containing alkaline filler with rosin size and size precipitant, returning broke from the paper making operation to the fibrous mix prior to web formation, and adding a size precipitant to the mix just prior to web formation.
18. The cyclic procedure in a method for manufacturing sized paper filled with alkaline filler comprising treating a fibrous web containing alkaline filler with rosin size and alum, returning broke from the paper making operation to the fibrous mix prior to web formation, and adding a size precipitant to the mix just prior to web formation.
19. The cyclic procedure in a method for manufacturing sized paper filled with alkaline filler comprising treating a fibrous web containing alkaline filler with rosin size and alum, returning broke from the paper making operation to the fibrous mix prior to web formation, and adding alum to the mix just prior to web formation.
20. The cyclic procedure in a method for manufacturing sized paper filled with alkaline filler comprising treating a fibrous web containing alkaline filler with rosin size and alum, returning broke from the paper making operation to the beater, and adding alum to the paper making mix just prior to web formation.
21. The method of manufacturing sized paper filled with alkaline filler comprising the inclusion in a fibrous web containing alkaline filler comprising calcium carbonate of substantially water-insoluble precipitated sizing material, said inclusion taking place subsequent to the point of delivery to a web-forming device of the fibrous mix from which said web is formed, and the subsequent drying of said web.
22. The method of manufacturing sized paper filled with alkaline filler comprising the inclusion in a fibrous web containing alkaline filler comprising calcium carbonate and magnesium com.

- 5 pound of substantially water-insoluble precipitated sizing material, said inclusion taking place subsequent to the point of delivery to a web-forming device of the fibrous mix from which said web is formed, and the subsequent drying of said web. 80
- 10 23. The method of manufacturing sized paper filled with alkaline filler comprising the inclusion in a fibrous web containing alkaline filler comprising calcium carbonate magnesium hydroxide of substantially water-insoluble precipitated sizing material, said inclusion taking place subsequent to the point of delivery to a web-forming device of the fibrous mix from which 85 said web is formed, and the subsequent drying of said web. 90
- 15 24. The step in a method of manufacturing sized paper filled with alkaline filler comprising the application to a fibrous web containing alkaline filler of precipitated sizing material subsequent to the point where said web leaves the web-forming device. 95
- 20 25. The step in a method of manufacturing sized paper filled with alkaline filler comprising the application to a fibrous web containing alkaline filler of substantially water-insoluble sizing compound containing metallic radical. 100
- 25 26. The step in a method of manufacturing sized paper filled with alkaline filler comprising the application to a fibrous web containing alkaline filler of substantially water-insoluble resinate. 105
- 30 27. The steps in a method of manufacturing sized paper filled with alkaline filler comprising applying sizing agent in aqueous solution to a fibrous web containing alkaline filler, and then effecting the conversion of said applied sizing agent into a substantially water-insoluble form. 110
- 35 28. The steps in a method of manufacturing sized paper filled with alkaline filler comprising applying an aqueous solution of rosin size to a fibrous web containing alkaline filler, and then effecting the conversion of said applied rosin size into a substantially water-insoluble form. 115
- 40 29. The step in a method of manufacturing sized paper filled with alkaline filler comprising effecting the precipitation of size in a fibrous web containing alkaline filler to form substantially water insoluble sizing. 120
- 45 30. In a method of manufacturing paper filled with alkaline filler wherein sizing agent is employed, wherein material is applied to a web containing alkaline filler, and wherein there is produced by the action of size precipitant applied to 125 said web substantially water-insoluble substance capable of imparting sizing effect to said web, that step comprising the application to said web of said size precipitant. 130
- 50 31. In a method of manufacturing paper filled with alkaline filler wherein sizing agent is employed, wherein material is applied to a web containing alkaline filler, and wherein there is produced by the action of acidic material applied to 135 said web substantially water-insoluble substance capable of imparting sizing effect to said web, that step comprising the application to said web of said acidic material. 140
- 55 32. In a method of manufacturing paper filled with alkaline filler wherein sizing agent is employed, wherein material is applied to a web containing alkaline filler, and wherein there is produced by the action of metallic salt applied to 80 said web substantially water-insoluble substance capable of imparting sizing effect to said web, that step comprising the application to said web of said metallic salt. 85
- 60 33. In a method of manufacturing paper filled with alkaline filler wherein sizing agent is employed, wherein material is applied to a web containing alkaline filler, and wherein there is produced by the action of alum applied to said web substantially water-insoluble substance capable of imparting sizing effect to said web, that step comprising the application to said web of said alum. 90
- 65 34. In a method of manufacturing paper filled with alkaline filler, the steps comprising preparing a fibrous mix, incorporating size precipitant as an ingredient of said mix, forming a web from said mix, and applying sizing agent to said web to form substantially water-insoluble sizing. 95
- 70 35. In a method of manufacturing paper filled with alkaline filler, the steps comprising preparing a fibrous mix, incorporating metallic salt as an ingredient of said mix, forming a web from said mix, and applying sizing agent to said web. 100
- 75 36. In a method of manufacturing paper filled with alkaline filler, the steps comprising preparing a fibrous mix, incorporating alum as an ingredient of said mix, forming a web from said mix, and applying sizing agent to said web. 105
- 80 37. In a method of manufacturing paper filled with alkaline filler, the steps comprising preparing a fibrous mix, incorporating size precipitant as an ingredient of said mix, forming a web from said mix, and applying rosin size to said web. 110
- 85 38. In a method of manufacturing paper filled with alkaline filler, the steps comprising preparing a fibrous mix, incorporating alum as an ingredient of said mix, forming a web from said mix, and applying rosin size to said web. 115
- 90 39. In a method of sizing paper filled with alkaline filler wherein a fibrous mix is run off on a web-forming device, the improvement comprising incorporating sizing in the fibrous mix, and thereafter imparting additional sizing to one side of the web formed therefrom. 120
- 95 40. In a method of sizing paper filled with alkaline filler wherein a fibrous mix is run off on a web-forming device, the improvement comprising incorporating sizing in the fibrous mix by means of size and acidic material, and thereafter imparting additional sizing to the web formed from said mix. 125
- 100 41. Filled paper comprising fibrous material, alkaline filler, sizing incorporated therein, and additional sizing on one side thereof. 130
- 105 42. Filled paper comprising fibrous material, alkaline filler, sizing precipitated by acidic material incorporated therein, and additional sizing on the surface thereof. 135

HAROLD ROBERT RAFTON.
